New York, N.Y. 10024

Filed June 25, 1973, Ser. No. 373,478

Term of patent 14 years

Int. Cl. D6—01

U.S. Cl. D6—6

FIG. 1 is a front, top and left side perspective view of a combined crib and dressing table showing my new design in the dressing table position; and

FIG. 2 is a front, top and right side perspective view in the crib position.

The rear of the combined crib and dressing table is a mirror image of the front, except for the lower rear vertical surface, which is substantially planar and unornamented. Portions of the webbing have been omitted for convenience of illustration.

I claim:

The ornamental design for a combined crib and dressing table, substantially as shown and described.
